UNITED STATES PATENT OFFICE.

SYLVESTRE KRANKA, OF PARIS, FRANCE.

BOTTLE-SEALING DEVICE.

1,029,450.

Specification of Letters Patent. Patented June 11, 1912.

Application filed June 28, 1909. Serial No. 504,909.

To all whom it may concern:

Be it known that I, SYLVESTRE KRANKA, a subject of the Emperor of Austria-Hungary, residing at Paris, in France, have invented a certain new and useful Bottle-Sealing Device, of which the following is a specification.

Numerous arrangements of stoppers with corrugated collars have been designed, but 10 none of them has proved completely satisfactory. The best system seems to be that described in the United States Patent No. 468,226 granted to William Painter, February 2, 1892, and consisting of a capsule, the 15 collar of which forms a succession of hollows and ribs, and of which the only disadvantages are that it is difficult to open, that it cannot be used for closing receptacles or other articles of small resistance, and that it 20 can be tampered with. In fact, the said stopper can be replaced after having been removed, so that no trace of fraudulent manipulation thus effected is left.

The invention remedies the above disadvantages.

It relates to improvements made in the same arrangement, which will be clearly understood with the assistance of the following description and the accompanying 30 drawing.

Figure 1 of the drawing shows, partly in elevation and partly in section, a construction of stopper in which some of the present improvements are embodied. Figs. 2 and 3 35 show on an enlarged scale, respectively in section and in elevation, a portion of the collar of the construction shown in Fig. 1. Figs. 4—5 and 6—7 show in the same way two modified constructions of the said collar. Fig. 8 shows in elevation, ready to be 40 placed on a neck with double ring, a complete stopper with a collar of the kind shown in Figs. 6 and 7. Fig. 9 shows in the same way, but in position, the construction shown in Fig. 8. Fig. 10 shows in elevation a modified construction of the tongues 45 with which the stopper forming the subject of this invention is provided.

These improvements consist chiefly in applying to the capsules of the above mentioned type the well known device consti- 50

tuted by tongues and hitherto utilized only for stoppers without corrugated collars, in which, for the purpose of rendering them practical, it was necessary to use either a 55 series of slots or some other weakening means, combined with the tongues, or else to use a very large number, or very large tongues.

The present improvements relate, moreover, to special constructions of the above application which enable the various elements constituting the collar, to execute at the moment when the closing is being effected, the relative movements necessary 60 for producing the closing and also enable the capsules themselves to be stamped out in one single operation of the press. According to these last methods of construction, recourse is had, as the means of 65 strengthening (which as well known is always necessary) the tongues themselves, on the one hand, to the ribs *b* of the collar, and on the other hand, either, as shown in Fig. 1, to an extension of the recess of the hollow 70 or hollows or reentering portions *a* which each tongue *c* touches, or as shown in Figs. 8—10, to a combination of projecting longitudinal and transverse ribs, this enabling in addition to what has already been stated, 75 the uncorking or opening to be effected with great facility. When, in fact, one of the tongues *c* (or the tongue, if there be only one) is moved upward as usual, the corresponding portion of the collar is bent about 80 a line passing practically through the top of the ribs adjoining the tongue manipulated, and the result is that, on the one hand, the portions of the collar situated on both sides of the tongue which is manipulated 85 are raised, and on the other hand, the capsule is torn. As the tearing takes place without fail when the tongue is operated for pushing it upward, which is a necessary condition for opening, the result is that the 90 system is practically proof against tampering, as it cannot be fraudulently opened except by acting by means of a suitable tool on the portions of the collar situated between the tongues, and at the same time 95 taking care not to touch the tongues. The said tearing affecting, moreover, only the 100

height of the collar of the capsule, that is to say, the desired height for facilitating the opening, the said capsule remains intact as regards its upper portion, so that it can be 5 still utilized as a cover.

In order to make the impossibility of tampering more certain, it is possible, (in view of the fact that the use of tongues renders it unnecessary to have recourse to the shape 10 hitherto used for the reëntering portions of the collar, to which portions it was usual to give, in section and elevation, a shape similar to that shown in Figs. 2 and 3, so as to leave between the base of the capsule and 15 the neck of the bottle or other receptacle, a certain annular space for introducing the opening tool) to give the said reëntering portions, such a shape that they should have in section and in elevation a form such as 20 shown in Figs. 4 and 5. It is then merely necessary to have one weak point in the system; the projection *d* forming the bottom portion of the ribs *b* which however might possibly be attacked by means of a tool. In 25 order to remove this last possibility of fraudulent tampering, it is sufficient to do away with the bottom portion of the reëntering parts, owing to which it becomes possible to give to the ribs or projecting 30 parts *b* a pointed shape such, for instance, as that shown in Figs. 6 and 7, owing to which, moreover, the forcing back of the said reëntering portions, required for closing the bottle, becomes much easier than was 35 the case hitherto. The said parts which can be made so that they extend farther in the direction of the height, and also made to project farther inward at the moment of stamping out, can be thus made to fit the 40 shape of the ring of the bottle or vessel completely, and the whole capsule can be made of much thinner metal (or other material) than usual, so as to render it suitable for closing articles of slight resistance and 45 made in a cheaper manner.

In the last case considered, the sectional form of the collar is similar to that previously mentioned and shown in Fig. 2, with the difference that there are no horizontal portions such as *d* Fig. 4, or practically none, at the base of the ribs. There is still left therefore between the bottom portion of the ribs and the ring of the article closed, a space suitable for the introduction 50 of a tool; but the system nevertheless cannot be tampered with. In fact, owing to the fragility of these ribs when they are constructed as described, as soon as an attempt is made to remove them from the 55 neck, they break or become permanently deformed, or tear. It is, moreover, easy to prevent entirely any possibility of attacking ribs designed in the above mentioned manner, by providing a groove in the closing ring on the neck of the article to be 60

closed, or, still better, by making the same ring double as shown in Figs. 8 and 9. This arrangement which is generally used for closing systems different from the one under consideration, was hitherto inapplicable 70 to the latter. It would have, in fact, rendered the opening impossible. According to this invention, on the contrary, the application in question becomes very simple, without any difficulty in opening. As however 75 in the case under consideration the second ring would interfere with the correct placing of the tongues, if they were made concave as shown in Fig. 1, the said tongues are preferably given a form such as shown 80 in Figs. 8 and 9, and obtained by bending the tongues inward twice, the first time about their symmetrical axis, which produces on the said tongues a more or less pronounced longitudinal rib *e*, and the second time about 85 the line or lines *f* connecting the points of the ribs adjoining the tongues, the result of which is that this line or lines are rendered more or less projecting. The first bending operation enables the tongues *c* to bend 90 again, as is necessary, during the closing operation proper, and helps to stiffen them in the direction of their height, while the second bending contributes to the facility of the same execution which would be otherwise interfered with by the second ring. 95

It is generally advantageous to design the tongues *c* so that they should adjoin three ribs, as shown in Figs. 8 and 9, and it is better in any case to extend the ribs, limiting them, along a certain length of the tongues as shown, for instance, in Fig. 10. 100

It is obvious that the invention is by no means limited to the constructions described. It comprises, on the contrary, any modifications such as those, for instance, in which smaller resistance, or even no resistance at all, is given to the portions of the capsule comprised between the tongues, which latter are thus caused to play the greater part or 110 even the whole function of the system. 105

In any case it must be understood that the system to which Figs. 8-10 relate, is by no means limited to the use with the double ring; the said system, can on the contrary, 115 be used with advantage in the case of a single ring.

What I claim as my invention and desire to secure by Letters Patent is:—

The combination with a bottle having 120 a head provided with an annular locking shoulder, of a capsule corrugated into locking contact with said shoulder and provided with extended reëntering portions in relation to a part of the corrugations to increase the extent of the capsule in the direction of its height, the capsule also being provided with depending tongues extending from a part of the corrugations and in alignment with a part of the reëntering portions 125 130

between the corrugations from which the tongues extend, whereby when the tongues are moved upwardly by manual force the portions of the capsule thereabove are bent
5 on a line passing approximately through the top portions of the adjacent corrugations.

In testimony whereof I have signed my

name to this specification in the presence of two subscribing witnesses.
